(57) **CLAIM**

We claim the ornamental design for a vehicle kitchen, as shown and described.

DESCRIPTION

FIG. 1 is a perspective view of the vehicle kitchen of the present disclosure;

FIG. 2 is a front elevational view of the vehicle kitchen of FIG. 1;

FIG. 3 is a rear elevational view of the vehicle kitchen of FIG. 1;

FIG. 4 is a left side elevational view of the vehicle kitchen of FIG. 1;

FIG. 5 is a right side elevational view of the vehicle kitchen of FIG. 1;

FIG. 6 is a top plan view of the vehicle kitchen of FIG. 1; and,

FIG. 7 is a bottom plan view of the vehicle kitchen of FIG. 1.

The broken lines showing vehicle kitchen features are provided for the purposes of illustrating environmental structures that form no part of the claimed design.
